US00D939575S

(12) **United States Design Patent** (10) **Patent No.:** **US D939,575 S**
(45) **Date of Patent:** **** Dec. 28, 2021**

(54) **ELECTRONIC DEVICE WITH ICON**

(71) Applicant: **Apple Inc.**, Cupertino, CA (US)

(72) Inventors: **Dylan Otto Boelte**, Berkeley, CA (US);
Alexander Charles MacLean, San
Jose, CA (US); **Wyatt R. Mitchell**, San
Francisco, CA (US); **Diego Monzon**
Del Pino, Cupertino, CA (US)

(73) Assignee: **Apple Inc.**, Cupertino, CA (US)

(**) Term: **15 Years**

(21) Appl. No.: **29/757,572**

(22) Filed: **Nov. 6, 2020**

CLAIM

The ornamental design for an electronic device with icon, as
shown and described.

DESCRIPTION

The file of this patent contains at least one drawing/photograph
executed in color. Copies of this patent with color
drawing(s)/photograph(s) will be provided by the Office
upon request and payment of the necessary fee.

FIG. 1 is a front view of an electronic device with icon
showing the claimed design;

FIG. 2 is another embodiment thereof; and,

FIG. 3 is another embodiment thereof.

The outer dashed broken lines in the figures show an
electronic device having a display screen and form no part
of the claimed design.

1 Claim, 2 Drawing Sheets
